UNITED STATES PATENT OFFICE.

WILLIAM SHERMAN BROWN, OF KNOXVILLE, TENNESSEE.

STEAM-ENGINE VALVE-GEAR.

1,260,313.

Specification of Letters Patent. Patented Mar. 26, 1918.

Application filed July 12, 1915. Serial No. 39,330.

To all whom it may concern:

Be it known that I, WILLIAM SHERMAN BROWN, a citizen of the United States, residing at Knoxville, in the county of Knox and 5 State of Tennessee, have invented a new and useful Improvement in Steam-Engine Valve-Gear, of which the following is a specification, reference being had to the accompanying drawing.

10 My improvement relates particularly to mechanism for transmitting motion from the drive wheel or axle of a steam locomotive to the distributing valve which admits steam to the cylinder.

15 The object of the improvement is to provide a construction which is simple, has the parts accessibly located, and which avoids irregularity of valve action due to lost motion or "pounding" at the crank.

20 This improvement is analogous to the mechanism described by my United States Patent No. 1,033,532, granted July 23, 1912, for "steam-engine valve-gear," (reissued July 14, 1914, No. 13,770), and by my United 25 States Patent No. 1,100,668, granted June 16, 1914, for "steam engine valve gear."

In the accompanying drawings,

Figure 1 is a side elevation, portions being broken away, showing my improvement applied to one side of a locomotive;

Fig. 2 is a plan of a portion of the mechanism shown by Fig. 1;

Fig. 3 is a section on the line, 3—3, of Fig. 2, looking toward the right;

35 Fig. 4 is a section on the line, 4—4, of Fig. 2, looking in the direction of the arrow;

Fig. 5 is a plan of the bridge which forms a support for portions of the mechanism;

Fig. 6 is a side elevation of said bridge;

40 Fig. 7 is a section on the line, 7—7, of Fig. 1, looking toward the left;

Fig. 8 is a horizontal section on the line, 8—8, of Fig. 1;

45 Fig. 9 is a section on the line, 9—9, of Fig. 1.

Referring to said drawings, 1 is the usual valve stem extending to the distributing valve (not shown). The usual horizontal, parallel cross-head guide bars, 2, are supported at their rear ends by the guide yoke extension, 3. The usual connecting rod or pitman, 4, is coupled to the usual main crank, 5, carried by a drive wheel, D. On the main crank, 5, is rigidly mounted an auxiliary crank, 6, standing 90 degrees forward of the main crank. To said auxiliary

crank is coupled one end of the auxiliary pitman rod, 7.

A bridge, B, is located above the frame, A; and extends from the ordinary guide 60 yoke, 8, and the guide yoke extension, 3, to the cross beam or plate, 10, and is secured to said guide-yoke and to said cross-beam by means of bolts, 9. Said bridge is in the form of a plate having its length horizontal 65 and being turned to bring its long edges into an upright plane. At its rear end, the bridge has a lateral extension, 11, resting against the cross beam, 10, and receiving said bolts, 9. At its forward end the bridge 70 has a transverse extension, 12, reaching to both sides of the body of the bridge and resting against the guide yoke extension, 3, and receiving said bolts, 9. Said bolts extend through the transverse extension, 12, and the 75 guide yoke, 8, whereby the forward end of the bridge is firmly secured to the guide yoke, and the guide yoke extension, the bridge being left clear between its ends. On the outer portion of the transverse extension, 80 12, and integral therewith is an ear, 13, which is directed rearward; and on the inner portion of said transverse extension is another ear, 14, also directed rearward and located horizontally opposite the ear, 13. 85 Each of said ears has a bearing, 15, receiving the ends of a shaft, 16. On said shaft is a bell crank or rocking member, C, preferably rotatable on said shaft, the latter being held immovably in its bearings. Said bell 90 crank has two approximately horizontal arms, 17, and a depending arm, 18. The latter arm is coupled to the valve-stem, 1. By rocking the bell-crank, the valve-stem is reciprocated endwise.

95 An approximately upright link, 19, has its upper end coupled to the arms, 17, of the bell crank, while its lower end is coupled to the forward end of the auxiliary pitman rod, 7, by a bolt, 20, both ends of said link being 100 forked to receive said rod and said arms, as shown in the drawings. Said arms, 17, are also forked to receive the upper ends of the link, 19.

In the bridge, B, is a horizontal slot, 21. 105 In said slot, is a slide block, E, by which is supported the lower end of a rocking member, F. Said member comprises two parallel plates, 22, placed at opposite sides of the slide block and the bridge. A bolt, 23, extends through the lower end of said plates 110 and the slide block. Each plate, 22, has at

its upper end a horizontal bearing, 24, extending toward the other of said plates and resting against the bearing, 24, of the other of said plates. On each of said bearings is 5 an upright extension, 25. A horizontal bolt, 26, extends transversely through said extensions and binds them together. A sleeve, 27, extends loosely through the bearings, 24, and is long enough to project slightly out of said 10 bearings. A bolt, 28, extends through said sleeve.

A link, 29, which is forked at each end, has its upper arms extending to opposite sides of the bridge and the rocking member, 15 F. At the upper end of each arm of said link is a bearing, 30, which is extended toward the other of said bearings and against the end of the sleeve, 27, so that a space is left between each of said arms and the adjacent plate, 22. The bolt, 28, also extends 20 through said bearings.

The fork at the lower end of the link, 29, extends to opposite sides of the auxiliary piston rod, 7. A bolt, 32, extends horizontally through said fork and the auxiliary rod, 7, said bolt being so placed on said rod as to be in substantially upright alinement with the axis of the slide block when the latter is in its middle position and the auxiliary 25 crank is on its upper or lower quarter.

The forward end of the auxiliary reach rod, 33, is forked and extends to opposite sides of the upper end of the link, 29, and the bolt, 28, extends through the arms of 30 the auxiliary reach rod as well as through the link, 29, and the bearings, 24, of the rocking member, F.

The rear end of said auxiliary reach rod is coupled to the upright rocking arm, 35, 40 which is rigid on the reversing shaft, 36, supported in bearings, 37. On said reversing shaft is an arm, 38, to which is coupled to the ordinary reversing lever, 40, working 45 on a sector or quadrant, 41. A sub-auxiliary reach rod, 42, forked at each end, has its forward end extending to each side of the lower portion of the rocking member, F. The bolt, 23, which extends through the 50 rocking member and the slide block, also extends through the adjacent portions of the sub-auxiliary reach rod.

The rear end of said sub-auxiliary reach rod extends to opposite sides of the upright 55 rocking arm, 35, which, as above stated, is rigid on the reversing shaft, 36; and a bolt, 43, extends horizontally through said rod and said upright arm.

When the auxiliary reach rod, 33, is 60 moved endwise by the tilting of the arm, 35, in response to endwise movement of the reach rod, 39, the sub-auxiliary reach rod is moved in the same direction, but not so far. Such movement of the sub-auxiliary 65 reach rod causes a corresponding sliding of

the slide block, E, and the bolt, 23. The axis of said bolt constitutes an axis of oscillation for the rocking member, F. Hence the curve through which the axis of the bolt, 28, is carried by the rocking of the member, F, 70 does not have for its axis the axis of the bolt, 23. On the contrary, the said curve is approximately on a radius centering on the axis of the bolt, 32, when the latter is in its middle position and the auxiliary crank 75 is on the upper or the lower quarter. The curve actually described by the axis of the bolt, 28, is the result of a compound movement, to wit: the tilting of the member, F, on the axis of the bolt, 23, and the bodily 80 sidewise movement or shifting of the bolt and the rocking member, the several parts concerned in the production of this compound movement being so proportioned and related to each other as to give said curve 85 an axis which coincides approximately with the axis of the bolt, 32, when, as above stated, the auxiliary crank, 6, is on the upper quarter or on the lower quarter.

During the rotation of the driver, D, the auxiliary rod, 7, is reciprocated endwise, its forward part being supported by the link, 29, which at this time oscillates on the axis of the bolt, 28, at the upper end of the rocking member, F. Said axis takes various 90 positions in the larger curve already described, according to the position into which the auxiliary reach rod, 33, and the rocker arm, 35, are set. The valve gear is "on center", when the axes of the bolts, 28, 23, 100 and 32, are in the same upright plane, at which time the auxiliary crank is on the upper or lower quarter.

During each reciprocation, said auxiliary pitman rod rocks bodily with the axis of 105 the bolt, 32, as a fulcrum. This involves the rising and falling of the forward end of said auxiliary rod, and during such movement of said end of said rod, the link, 19, is forced up and down, and such movement 110 of said link causes the rocking of the bell crank, C, and the reciprocation of the valve stem, 1.

The gear is reversed by throwing the reversing lever across the center in the usual 115 manner, and the opening of the valve is varied by moving the upper end of the link, 29, nearer to or farther from the center. When the rocking member has been brought to any desired stage of its movement it is 120 secured in such stage by engaging the reversing lever, 40, with the quadrant. When the upper end of the rocking member, F, is on center or in the middle of its curved path, the valve motion is reduced to the extent of the "lead".

By making provision for shifting the axis of the rocking member, F, it is made possible to carry the upper end of the rocking member along a curve the radius of which 130

approximately equals the length of the link, 29, although the rocking member is much shorter than the link, 29. If the axis of the rocking member were not thus made shiftable, said rocking member would have to be approximately as long as the link, 29, as is the case in the gear described in my above mentioned Patent No. 1,100,668, that gear having a hanger extending down from the 10 bridge low enough to support the axis of the rocking member in approximate alignment with the axis of the link which corresponds to the link, 29, of the gear of this application.

15 By thus shortening the rocking member, several advantages are obtained, among which may be mentioned the omission of the hanger, whereby greater stability is obtained. Furthermore, the rocking member 20 may be placed within the fork of the link, 29, whereby the parts are balanced by being supported symmetrically on an upright plane cutting the bridge lengthwise. This affords greater stability and durability, 25 diagonal strains on the rocking member, the link, and the bridge, being avoided.

It is to be observed that the reversing mechanism acts differentially on the rocking member, different portions of the rocking member being carried through different distances. Hence, we have in this combination of elements a differential reversing mechanism. This differential characteristic comes through the rocker arm, 35, the auxiliary reach rod, 33, and the sub-auxiliary reach rod, 42, the rocker arm imparting to 30 said reach rods different ranges of movement, and said rods imparting different movements to the upper and lower portions 35 of the rocking member.

40 I claim as my invention,

1. In a valve gear, the combination of a frame, a distributing valve stem, a rocking member, means in operative relation with 45 said member at two elevations for rocking and bodily reciprocating it sidewise and securing it at any stage of its movement, an auxiliary rod, means for actuating said rod, means operatively relating said rod to said 50 rocking member, and means for connecting said rod and the stem of the distributing valve, substantially as described.

2. In a valve gear, the combination of a frame, a distributing valve stem, a rocking member, means in operative relation with 55 said member at two elevations for rocking and bodily reciprocating it sidewise and securing it at any stage of its movement, an auxiliary rod, means for actuating said rod, 60 a link operatively relating said rod to said rocking member, and means for connecting said rod and the stem of the distributing valve, substantially as described.

3. In a valve gear, the combination of a 65 frame, a distributing valve stem, a rocking

member, means in operative relation with said member at two elevations for simultaneously rocking and bodily reciprocating it sidewise and securing it at any stage of its movement, an auxiliary rod, means for 70 actuating said rod, means operatively relating said rod to said rocking member, and means for connecting said rod and the stem of the distributing valve, substantially as described. 75

4. In a valve gear, the combination of a frame, a distributing valve stem, a rocking member, means in operative relation with said member for simultaneously rocking and bodily reciprocating it sidewise and securing it at any stage of its movement, an auxiliary rod, means for actuating said rod, a link operatively relating said rod to said 80 rocking member, and means for connecting said rod and the stem of the distributing valve, substantially as described. 85

5. In a valve gear, the combination of a frame, a distributing valve stem, a rocking member, means in operative relation with said member for rocking and bodily reciprocating it sidewise and securing it at any stage of its movement, an auxiliary rod, means for actuating said rod, a link operatively relating said rod and said rocking member, and means comprising a bell-crank 90 for connecting said rod and the distributing valve, substantially as described. 95

6. In a steam engine valve gear, the combination of a distributing valve stem, a rocking member, a support upon which said 100 rocking member is bodily shiftable sidewise, reversing mechanism in operative relation with the upper portion and the lower portion of said rocking member to reciprocate said member bodily sidewise, the upper portion being moved faster and farther than the lower portion during each reciprocation, and securing said rocking member in any stage of its movement, an auxiliary crank, 105 an auxiliary rod having one end coupled to said crank, an approximately upright link coupled to said auxiliary rod and to the upper portion of said rocking member, and means for connecting said auxiliary rod into operative relation with the stem of the distributing valve, substantially as described. 110 115

7. In a steam engine valve gear, the combination of a distributing valve stem, a rocking member, a support upon which said 120 rocking member is bodily shiftable sidewise, reversing mechanism in operative relation with the upper portion and the lower portion of said rocking member to reciprocate said member bodily sidewise, the upper portion being moved faster and farther than the lower portion during each reciprocation, and securing said rocking member in any stage of its movement, an auxiliary crank, 125 an auxiliary rod having one end coupled to said crank, an approximately up- 130

right link coupled to said auxiliary rod and to the forward portion of said rocking member, and means comprising a bell-crank for connecting said auxiliary rod into operative relation with the stem of the distributing valve, substantially as described.

8. In a steam engine valve gear, the combination of a distributing valve stem, a bridge, a rocking member slidably supported by said bridge, a reversing lever in operative relation with said rocking member at two elevations, for rocking and bodily shifting said member along said bridge, an auxiliary crank, an auxiliary rod having one end coupled to said crank, an approximately upright link coupled to said auxiliary rod and having its upper end coupled to the free portion of said rocking member, and means connecting said auxiliary rod into operative relation with the stem of the distributing valve, substantially as described.

9. In a steam engine valve gear, the combination of a distributing valve stem, a rocking member, a slidable support for said rocking member, a reversing member in operative relation with the said slidable support for reciprocating said support sidewise, another reversing member in operative relation with the upper portion of said rocking member for reciprocating said portion of said member bodily sidewise farther than the lower portion of the rocking member is reciprocated, means for securing said reversing members in any stage of their movements, an auxiliary rod, means for actuating said rod, an approximately upright link coupled to said auxiliary rod and to the upper portion of said rocking member, and means for connecting said auxiliary rod into operative relation with the stem of the distributing valve, substantially as described.

10. In a steam engine valve gear, the combination of a distributing valve stem, a rocking member, a slidable support for said rocking member, a rocking arm, a reversing member connected to said rocking arm and to the slidable support, another reversing

member connected to the upper portion of the rocking member and to the rocking arm outward of the connection of said arm with the other reversing member, means for rocking said rocking arm and securing it in any stage of its movement, an auxiliary rod, means for actuating said rod, an approximately upright link coupled to said auxiliary rod and to the upper portion of said rocking member, and means for connecting the auxiliary rod into operative relation with the stem of the distributing valve, substantially as described.

11. In a steam engine valve gear, the combination of a distributing valve stem, a bridge, a rocking member extending to opposite sides of and slidably supported upon said bridge, a forked link extending upward along opposite sides of said bridge and said rocking member and being coupled to the upper part of said rocking member, reversing mechanism in operative relation with said rocking member at two elevations for bodily reciprocating said member sidewise, the upper portion being given a longer path than the lower portion, means for securing the reversing mechanism in different positions, an auxiliary rod coupled to the lower end of said link, means for actuating said auxiliary rod, and means for operatively connecting said rod with the stem of the distributing valve, substantially as described.

12. In a valve gear, the combination of a frame, a distributing valve stem, a rocking member, differential reversing mechanism engaging the rocking member for reciprocating it sidewise and securing it at any stage of its movement, an auxiliary rod, means for actuating said rod, means operatively relating said rod to said rocking member, and means connecting said rod and the stem of the distributing valve, substantially as described.

In testimony whereof I have signed my name, in presence of two witnesses, this 29th day of June, in the year one thousand nine hundred and fifteen.

WILLIAM SHERMAN BROWN.
